DOLLY

Peter E. Geldhof, Syracuse, N. Y., assignor to
 Easy Washing Machine Corporation, Syracuse,
 N. Y., a corporation of Delaware

Application February 16, 1931. Serial No. 516,074

3 Claims. (Cl. 259—101)

This invention relates to a new and improved dolly. circular substantially flat bottom disk or portion 6.

In washing machines of the dolly type in which the dolly is oscillated to cause agitation of the clothes in the washing fluid, the design of the dolly itself controls to a very considerable degree the speed and thoroughness of the washing operation.

It is important that the dolly be so designed that the clothes are subjected to a very thorough agitation in the washing fluid and it is also important that during the washing operation they be subjected to a rubbing operation in order to facilitate the loosening of the dirt particles carried by them and their elimination from the clothes themselves.

The main object of my invention is to provide a dolly of such a shape that all of the clothes contained in the washing vat will be thoroughly agitated irrespective of their positions in the vat.

Another object is to provide a dolly of such a shape that the clothes will be subjected to a thorough rubbing during the washing operation.

Other objects and advantages relate to the size, shape and arrangement of parts all as will more fully appear from the following description taken in connection with the accompanying drawings in which:—

30 Figure 1 is a perspective view of my improved dolly.

Figure 2 is a vertical section through the vat of the washing machine with my dolly in position therein.

35 Figure 3 is a section on line 3—3 of Figure 2.

Figure 4 is a section on line 4—4 of Figure 3.

My invention is directed to the dolly itself and it is obvious that the dolly may be used in any desired shape of vat and may be oscillated by various mechanisms, but for the purpose of explaining my invention, I have here shown the dolly 1 in position in a circular vat 2 supported on a main frame 3 and in Figure 2, I have partially indicated a driving mechanism 4.

45 As said above, any appropriate driving mechanism may be used, but I have found that very successful operation of a dolly may be obtained by the use of a driving mechanism such as that shown and described in Patent No. 1,789,939 for a Washing machine issued January 20, 1931 to me as assignor to the Syracuse Washing Machine

50 Corporation.

The dolly 1 comprises a vertically extending tubular portion or hollow post which merges 55 along gradually curved lines into the center of a

circular substantially flat bottom disk or portion 6.

In circumferentially spaced relation on portions 5 and 6, I provide a plurality of radially extending main vanes 7 here illustrated as three 60 in number.

Each main vane 7 is substantially L-shaped in form having a vertically extending upper portion 8 which projects radially from the tubular central portion 5 and tapering upwardly to a point adjacent the top of the post, and a radially extending portion 9 which extends vertically from the bottom portion 6 and having its upper edge inclined slightly downwardly and outwardly with its outer end terminating at the edge of portion 6 and 70 inclined slightly upwardly as it extends upwardly.

The bottom portion 9 of vane 7 extends vertically from bottom portion 6 a substantial distance so that it may engage the clothes being 75 washed to carry the same back and forth as the dolly 1 is oscillated, the upper portion 8 of vane 7 also engaging the clothes and assisting in such carrying and agitation of the clothes.

Intermediate vanes 7 and in spaced relation thereto I provide auxiliary vanes 10. Each vane 10 has an upper portion 11 similar in size and shape to the upper portion 8 of vane 7 and a bottom portion 12 which extends radially to the edge of the bottom portion 6. 85

The bottom portion 12 of vane 10 extends vertically from the bottom portion 6 only a short distance and preferably less than one half the upward extension of the portion 9 of vanes 7, and as the lower part of the portion 11 curves 90 outwardly where it meets the disk 6 it decreases in radial extension so as to merge symmetrically with portion 12. An important feature of this invention resides in the structural fact that the outer edge of each vane 9 and 10 is provided with 95 a bead 20 and 21 respectively, substantially circular in cross section and a diameter somewhat greater than the thickness of the vane so as to project symmetrically some distance on opposite sides of the respective vanes to provide small air 100 spaces between the clothes and the vane at the base of the bead, as the dolly oscillates.

During this operation, the vanes 7 will engage the clothes and subject them to a rubbing action and at the same time will tumble them about 105 on each other.

The upper portions 11 of the vanes 10 will assist in moving the clothes in the vat and the lower portions 12 of vanes 10 being beneath the greater portion of the clothes, will subject the clothes 110

with which they come in contact, to a very effective rubbing operation.

During the washing operation, the clothes will change their relative position and will move not only circumferentially of the vat but up and down therein, so that all of the clothes will eventually receive the benefit of the rubbing action of the lower portion 12 of the vanes 10.

I have here shown three high vanes and three low vanes, but it will be understood that the movement of vanes and their exact position in relation to each other may be varied if desired, although I prefer to have low vanes intermediate adjacent high vanes.

It also will be understood that the dolly 1 may be secured to the oscillating drive shaft 13 of the driving mechanism 4 in any convenient way and as one means of so securing the dolly 1 in position, I have shown in the upper end of the tubular portion 5 a plurality of circumferentially spaced grooves 14 adapted to be engaged by splines 15 on the upper end of shaft 13.

Although I have shown and described a particular arrangement of parts and a dolly having a particular number of vanes, it will be understood that various changes and modifications may be made, for although I have shown and described a specific structure and form and arrangement of parts as an exemplification of an embodiment of my invention, I do not desire to restrict myself to the exact size, shape or arrangement of parts, as various changes may be made within the scope of the appended claims.

I claim:

1. In a clothes washing machine, a dolly comprising a substantially circular disk, a hollow post rising from the central portion of the disk, a plurality of vanes extending radially from the disk and post, each of said vanes consisting of a substantially horizontal portion extending upwardly from the base and terminating in a vertical portion extending outwardly from said post,

the vertical portion of said vanes being of substantially uniform structure and gradually decreasing in lateral extension from the horizontal portion upwardly, the horizontal portions of alternate vanes being of not more than one-half the vertical height of the corresponding portions of the remaining vanes.

2. In a clothes-washing machine, a vat having a normal fluid surface level, a dolly comprising a substantially circular flat disk mounted in said vat adjacent the bottom thereof, a central post portion rising upwardly from the disk, a plurality of primary vanes extending outwardly from the post portion and upwardly from the disk substantially to the normal surface level, said primary vanes extending outwardly on the surface of the disk to substantially the circumferential edge thereof, and a plurality of secondary vanes of substantially the same shape as the primary vanes interposed between alternate primary vanes, said secondary vanes being of less effective area than the primary vanes and serving to rub the clothes as they are dragged circumferentially by the primary vanes.

3. In a clothes-washing machine, a vat having a normal fluid surface level, a dolly comprising a substantially circular flat disk mounted in said vat adjacent the bottom thereof, a central post portion rising upwardly from the disk, a plurality of primary vanes, each of said primary vanes having a portion extending from said post and a portion extending upwardly from said disk, the portion of said blade extending from said post rising from the disk substantially to the normal surface level in the vat, and a plurality of secondary vanes interposed between alternate primary vanes, said secondary vanes extending outwardly from the post a lesser distance than the primary vanes and serving, when the clothes are carried circumferentially by the primary vanes, to exert a scrubbing action on the clothes.
